UNITED STATES PATENT OFFICE.

JACOB S. SAMMONS, OF MARSHALLTOWN, IOWA.

BILL-FILE.

SPECIFICATION forming part of Letters Patent No. 657,455, dated September 4, 1900.

Application filed January 6, 1900. Serial No. 586. (No model.)

To all whom it may concern:

Be it known that I, JACOB S. SAMMONS, a citizen of the United States, and a resident of Marshalltown, in the county of Marshall and State of Iowa, have invented certain new and useful Improvements in Bill-Files, of which the following is a specification.

This invention relates to that class of bill-files in which the bills or papers are punched before they are placed upon the rod or file proper, and is designed more especially as an improvement upon my prior patent, No. 459,471, dated September 15, 1891. In said patent the impaling-pin is provided with a point which forces its way through the paper in making a hole for the body of the pin, and in practice it is found that this method not only greatly increases the bulk of the paper around the pin, preventing the bills or papers lying flat, but also makes it inconvenient or difficult to lift a number of the bills or papers for the purpose of exposing one. The present invention, therefore, contemplates the production of a device that will fully overcome these objections by punching a hole in each paper before it is filed, the said hole being formed by removing a disk of the paper and is slightly larger than the rod or pin upon which the paper is filed, thereby permitting the papers to lie flat and making it easy to move them upon the pin or rod in exposing any one.

The device is more particularly adapted for filing doctors' prescriptions, as it provides for entirely separating the papers in refilling a prescription, so that the prescription to be refilled is the only one exposed.

An important feature of the invention is the provision of a pivoted plate or lift which receives the paper and automatically moves it above the head of the punch when said punch is operated to punch a hole into said paper, thereby freeing the paper from the head or enlarged portion of the punch and avoiding danger of tearing it in moving the same upon the rod.

The device also provides a receptacle for collecting the disks removed by the punch.

The following specification enters into a detail description of the construction and operation of my invention, reference being had

to the accompanying drawings, and to letters of reference thereon, which designate the different parts, and what I consider to be new in the construction and combination is more specifically set forth in the appended claims.

In the drawings, Figure 1 is a perspective view of a bill-file or prescription-file constructed in accordance with my present invention. Fig. 2 is a longitudinal sectional view. Fig. 3 is a transverse sectional view on a line with the punch.

In carrying out my invention the tablet or support A is made up of a bottom board A' and a top board A'', connected together at one end by a metal strip B and separated at their opposite end by a cross-piece C. The central part of the top board is cut away above the cross-piece and the body of the board is cut rearward, as shown at a a, forming a resilient portion or spring-board A³, to which is attached one part of the punch, hereinafter described. Extending across the front end of the tablet is a covering-plate D, secured in place by screws, which pass into the end portions of the top board and into the cross-piece, said covering-plate overlapping the front edge of the tablet. At the center of this plate is a hole E, through which the head of the punch, hereinafter referred to, passes in cutting a hole in the bill or paper, and in the rear of and at each side of said hole E the covering-plate is depressed to receive the lower part of a pivoted plate or lift F. The pivoted plate or lift is pivoted upon a pin G, passed through ears d d, formed at the rear end of the covering-plate, and comprises upper and lower sections, which are slightly separated to receive the bill or paper which is passed between them. The lift is formed of a single plate bent upon itself to present the sections between which the bill is passed, and in forming this lift a rearwardly-projecting tongue f is provided for operating the same. The forward end of the pivoted plate or lift is cut away, as shown, so as to embrace the head of the punch and secure a better hold upon the bill or paper and also form a guide for said punch. One end of the covering-plate is turned up to form a guide d'. Below the center portion of the covering-plate, between the ends of the top board, is left a space, in

which are collected the disks of paper removed by the punch, said space communicating with a chute H, through which the disks of paper are delivered.

- 5 I designates the rod upon which the bills or papers are filed, said rod being bent in the form of a loop presenting two members and is attached to the spring portion A³ of the top board by passing the end of the rear member through the same, being held in place by nuts *i.e.* The end of the forward member of the rod I is enlarged to form a punch head or cutter K, adapted to pass through the hole E, in the covering-plate, said cutter being normally located a slight distance above the opening to permit of the bill or paper being passed under the same. The spring-board A³ also carries a lip L, which engages the tongue projecting from the pivoted plate or lift and is for the purpose of operating said lift when the spring-board is depressed in the operation of the punch. A wire loop M is attached at its ends to the top board at each side of the free end of the spring-board, said loop being disposed at right angles to the rod I and passing under the upper curved portion of said rod, forming a guide for the bills or papers in moving them from one member of rod I to the other.
- 30 The lip L, carried at the free end of the spring-board A³, is formed of a single piece of sheet metal, which is bent upon itself and then shaped, as shown, to form the lip proper, while the ends receive the free end of the board A³ between them and are secured in place by the rod I.

The metal strip B by which the rear ends of the boards forming the tablet are connected together prevents them from warping and is formed into a roll at its upper end to present a handhold for the device and is of service more particularly in removing the device from a file-holder or cabinet in which it may be stored.

- 45 From the foregoing description, in connection with the accompanying drawings, the construction and operation of my improved bill-file will be readily understood, for in filing a bill or prescription one end thereof is passed under the head of the punch into the pivoted plate or lift and against the side gage or guide d'. The punch is then operated by striking upon the curved portion of the rod I, forcing the head K through the paper and 50 removing a disk of the paper which passes through the hole E of the covering-plate. Simultaneously with the operation of the punch the pivoted plate or lift F is actuated by the lip L engaging the tongue of said plate or lift and carries the paper upward upon the rod above the head of the punch. The bill or paper can then be readily grasped and moved upon the rod to the rear member and deposited upon the tablet or support, the 55 hole made by the head of the punch being larger than the body of the rod, permitting the paper or bill to be easily moved upon the

rod, while the loop M serves as a guide, so that each paper will lie perfectly straight upon the tablet and upon each other.

70 It will be noted that the fingers or forward ends of the lower section of the pivoted plate or lift are bent downward and pass through openings in the covering-plate in order that the bill or prescription will readily pass into said lift, and it will also be understood that the forward member of the rod I is sprung so that the head K at the lower end thereof will bear lightly against the pivoted plate or lift to insure its being properly centered over the hole E.

75 This device provides for readily filing papers that are required to be kept for future reference, and when used for filing prescriptions will remove the danger of making a 80 mistake where a large number of prescriptions are together, for in refilling a prescription those above the one to be refilled are moved over upon the forward member of the rod, face downward, while the one to be refilled is the only one that is exposed.

85 Having thus described my invention, what I claim as new, and desire to secure by Letters Patent, is—

90 1. In a bill-file, the combination, of a tablet or support, a plate having a hole therein, a curved rod provided with a head or cutter adapted to pass into said hole, a spring to which the curved rod is attached and supported, a pivoted plate having fingers between which the end of the paper to be punctured is passed, and means for automatically lifting the free end of said pivoted plate upon the operation of the curved rod, substantially as shown and for the purpose set forth.

95 2. In a bill-file, the combination, of a tablet or support, a plate having a hole therein, a curved rod provided with a head or cutter adapted to pass into said hole, a spring to which the curved rod is attached and supported, a pivoted plate having fingers between which the end of the paper to be punctured is passed, means for automatically lifting the free end of the pivoted plate upon the operation of the curved rod, and a wire 100 loop disposed across the tablet to form a guide, substantially as shown and for the purpose set forth.

105 3. In a bill-file, the combination, of a tablet or support, a plate having a hole therein, a curved rod provided with a head or cutter adapted to pass into said hole, a spring to which the curved rod is attached and by which it is supported, a lip projecting from the spring, and a pivoted plate having a 110 tongue engaged by the lip, said pivoted plate being also provided with fingers which embrace the head or cutter, substantially as shown and for the purpose set forth.

115 4. In a bill-file, the combination, of a tablet or support, a plate having a hole therein, a curved rod provided with a head or cutter adapted to pass into said hole, a spring to which the curved rod is attached and sup-

ported, a pivoted plate having fingers which embrace the head or cutter, means operating the pivoted plate from the spring which supports the curved rod or punch, a guide-loop 5 for the bill or paper, and a side gage at one side of the tablet, substantially as shown and for the purpose set forth.

5. In a bill-file, the combination, of the support or tablet made up of two boards connected together at one end and separated at the other end, the upper board being cut away as shown to form a spring, a plate located upon the tablet and provided with a hole therein, a curved rod attached to the afore- 10 said spring and provided with a head or cutter adapted to pass into the hole of the plate, a pivoted plate or lift supported upon the tablet, and means for operating the pivoted plate from the spring which supports the 15

curved rod or punch, substantially as shown 20 and for the purpose set forth.

6. In a bill-file, the combination, of the tablet or support, a plate having a hole therein, a curved rod having a head or cutter adapted to pass into said hole, a spring to which the 25 curved rod is attached and supported, a plate pivoted upon the tablet and having a rear-wardly-projecting tongue, a plate attached to the spring and adapted to engage the tongue of the pivoted plate, a side gage on the tablet, 30 and a wire loop passing under the curved rod; together with a metal strip securing the ends of the boards forming the tablet, substan- tially as shown and for the purpose set forth.
